UNITED STATES PATENT OFFICE.

ROBERT HERDLICKA, OF CHICAGO, ILLINOIS.

VENTILATOR.

1,427,463.

Specification of Letters Patent. Patented Aug. 29, 1922.

Application filed June 30, 1921. Serial No. 481,525.

To all whom it may concern:

Be it known that I, ROBERT HERDLICKA, a citizen of the United States, residing at Chicago, in the county of Cook and State of Illinois, have invented new and useful Improvements in Ventilators, of which the following is a specification.

The invention relates to improvements in ventilators.

10 The object of the present invention is to improve the construction of ventilators and to provide a simple, practical, durable and comparatively inexpensive construction adapted to protect a draft or eduction pipe 15 from rains, snow and the like and capable of preventing the wind from choking and entering with the operation of the said draft or eduction pipe and of catching currents of air from any direction and of causing the 20 same to produce upward currents in the device exteriorly of the draft or eduction pipe to cause a suction and positive circulation or upward draft through the pipe.

With these and other objects in view the 25 invention consists in the novel construction, combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the 35 invention:

In the drawings in which like characters of reference designate corresponding parts in the several figures;

Figure 1 is a side elevation of a ventilator 40 constructed in accordance with this invention.

Figure 2 is a central vertical sectional view of the same.

Figure 3 is a reverse plan view of the 45 ventilator.

Figure 4 is a detail view of one of the deflecting plates.

Figure 5 is a similar view of one of the connecting plates.

50 In the accompanying drawing in which is illustrated the preferred embodiment of the invention, the universal ventilator which may be constructed of any suitable material comprises in its construction a conical cap 1 and an intermediate trunco-conical section or member 2 located below the conical

cap and spaced from the same and from the upper end of a draft or eduction pipe 3. The intermediate section or member 2 which extends above and below the upper edge of 60 the vertical draft or eduction pipe 3 is provided at its upper edge with an upwardly projecting substantially cylindrical flange 4 which extends above the lower edge of the conical cap 1. The said intermediate section 65 or member 2 is also provided at its lower edge with an approximately cylindrical flange or portion 5 and the marginal edges or flanges of the conical cap and the intermediate section or member may be crimped or plain as desired. The lower edge of the cap 1 extends downwardly and forms a marginal flange 6 as clearly shown in Figure 2 of the drawing. The intermediate section or member 2 which forms the skirting around the 70 upper portion of the vertical pipe 3 is supported in spaced relation with the said pipe by means of angle brackets 7 constructed of relatively stout metal and composed of vertical arms or portions 8 and inclined arms 80 or portions 9 which are secured by rivets 10 and 11 to the pipe and to the intermediate section or member respectively. The vertical arms 8 are arranged interiorly of the pipe 3 and the inclined arms are located at the inner 85 or lower face of the intermediate section or member 2. The conical cap is supported above and in spaced relation with the intermediate section or member by approximately U-shaped brackets 12 composed of vertical 90 connecting portions and upper and lower outwardly extending inclined arms 13 and 14 arranged respectively at the inner or lower face of the conical cap 1 and at the outer or upper face of the intermediate section or member 95 2. The lower arms 14 are secured to the intermediate section or member by the rivets 11 and the upper arms are fastened to the conical cap by rivets 15.

The vertical pipe 3 is equipped with substantially oval deflecting plates 16 secured at diametrically opposite points to the vertical pipe by the rivets 10 of the brackets and curved horizontally as clearly shown in Figure 3 of the drawing and provided with marginal flanges 17 producing a slightly dished formation. The side portions of the deflecting plates curve outwardly and project from the vertical pipe 3 and are spaced apart and provided with laterally projecting attaching 110 flanges 18 to which are secured curved connecting plates 19. The deflecting plates 16

present outer concave faces while the connecting plates 19 present outwardly convex faces and the said plates 19 which are secured to the flanges 18 by rivets 20 extend 5 at their side edges over the deflecting plates as shown in Figure 3 to cooperate therewith to provide grooves or channels for directing the currents of air upwardly. The connecting plates 19 and the projecting side portions 10 of the deflecting plates also form channels 21 for directing the air upwardly. These upward currents of air pass through the space between the intermediate section or member and the upper end of the vertical pipe 3 and 15 they produce a suction and cause a positive upward draft through the vertical pipe 3. The arrangement of the conical cap and the intermediate section or member effectively shield the upper end of the pipe 3 from the 20 weather and prevent rain, snow, hail and the like from entering the pipe. Also any choking of the pipe by reason of the air blowing directly across the top of the same is also prevented by the protecting conical cap and intermediate section. The projecting side portions 22 of the connecting plates are preferably reinforced at the vertical edges at 23 by bending the metal on itself and the said projecting side portions 22 form wings or 28 portions and assist the deflecting plates in catching the air and producing the upward currents at the outer face of the plates 16. The lower portion of the dished deflecting 33 plates project below the connecting plates and the connecting plates are cut away at 35 their lower edges to form recesses 24 between the deflecting plates. As the ventilator is adapted to catch the currents of air from any direction, it is unnecessary to mount the ventilator for rotary movement and the ventilator is thereby enabled to operate as a universal ventilator in utilizing the wind blowing 40 from any direction.

What is claimed is:

45 1. A ventilator of the class described including a vertical pipe, a conical member or portion supported above the pipe in spaced relation with the same, deflecting plates secured to the exterior of the vertical pipe and dished to form grooves or channels and connecting plates secured to the deflecting plates at the side portions thereof and spaced from the vertical pipe to form channels or 50 passages for the air.

2. A ventilator of the class described including a vertical pipe, a conical member or portion supported above the pipe in spaced relation with the same, deflecting plates secured to the exterior of the vertical pipe and dished to form grooves or channels and connecting plates secured to the deflecting plates at the side portions thereof and spaced from the vertical pipe to form channels or 55 passages for the air, said connecting plates having their side portions projecting over the deflecting plates and cooperating therewith to catch the air and produce upward currents of the same.

3. A ventilator of the class described including a vertical pipe, approximately oval, 70 dished deflecting plates secured to the vertical pipe at the exterior thereof and presenting outer concave faces and connecting plates secured to the side portions of the deflecting plates and curved horizontally to 75 present outer convex faces and inner concave faces.

4. A ventilator of the class described including a vertical pipe, dished deflector plates secured to the pipe exteriorly thereof and provided at opposite sides with attaching flanges and forming grooves or channels and connecting plates secured to the attaching flanges of the deflecting plates and having side portions extending over 85 the deflecting plates.

5. A ventilator of the class described including a vertical pipe, dished deflecting plates secured to the exterior of the vertical pipe and presenting outer concave faces and 90 curved connecting plates secured to the side portions of the deflecting plates and projecting over the same, said deflecting plates being projected below the connecting plates and the latter being cut away at their lower 95 portions between the deflecting plates.

6. In a device of the class described the combination with a vertical pipe, a conical cap thereon, a plurality of curved deflecting plates secured to the upper end of said pipe 100 at diametrically opposite points thereon, and oppositely curved connecting plates secured to the side portions of the deflecting plates and projecting over the same.

In testimony whereof I have hereunto set 105 my hand.

ROBERT HERDLICKA.
